(57) **CLAIM**

The ornamental design for an electronic games apparatus, as shown and described.

DESCRIPTION

The patent or application file contains at least one drawing executed in color. Copies of this patent with color drawings will be provided by the Office upon request and payment of the necessary fee.

FIG. 1 is a front perspective view of an electronic games apparatus showing my new design;

FIG. 2 is a rear elevation view of the electronic games apparatus shown in FIG. 1;

FIG. 3 is a right side elevation view of the electronic games apparatus shown in FIG. 1;

FIG. 4 is a left side elevation view of the electronic games apparatus shown in FIG. 1;

FIG. 5 is top perspective view of the electronic games apparatus shown in FIG. 1; and,

FIG. 6 is a bottom plan view of the electronic games apparatus shown in FIG. 1.

1 Claim, 6 Drawing Sheets
